UNITED STATES PATENT OFFICE.

WALTER P. MURPHY, OF CHICAGO, ILLINOIS.

CENTERING DEVICE FOR CAR COUPLINGS.

1,415,463.

Specification of Letters Patent.

Patented May 9, 1922.

Application filed December 30, 1919. Serial No. 348,286.

To all whom it may concern:

Be it known that I, WALTER P. MURPHY, a citizen of the United States, residing at Chicago, in the county of Cook and State 5 of Illinois, have invented certain new and useful Improvements in Centering Devices for Car Couplings, of which the following is a specification.

When cars are on sharp curves, such as 10 are used in industrial plants and at terminals, it is frequently necessary to position the coupler in the center line of the car so that couplers on adjacent cars will automatically engage when they come together. It is customary to elevate the outside rail on a curve, therefore, when a car 15 equipped with a swinging carrier iron is used the coupler has a tendency to move to the inside of the curve.

When a brakeman is making a coupling 20 it is necessary for him to position the coupler on a standing car in line with the on coming car, otherwise they are liable not to couple. In the case of a car equipped with 25 a swinging carrier iron, in which the coupler had moved to the inside of the curve, the brakeman would be compelled to hold the coupler over either by foot or hand which is not only dangerous to his life and 30 limb but is contrary to the laws in a great many States.

The object of my invention is to provide means to temporarily retain the coupler in proper position until the cars are coupled, 35 which coupling will automatically disengage the said means after which the coupler is free to accommodate itself to service movements; with this and other objects in view my invention consists in the parts and 40 combination of parts as will be hereinafter more fully set forth.

Figure 1 is a detailed perspective view of 45 a car end sill construction and associated parts with my invention embodied.

Figure 2 is a front elevation of a buffer block, swinging carrier iron and coupler, the 50 coupler being sectional with my invention embodied.

Figure 3 is a detailed sectional view 55 through the buffer and carrier iron, with a coupler in elevation, showing my invention in position for centering the coupler.

The reference numeral 1 designates an end sill of any approved construction to 55 which the buffer block 2 is suitably secured. A coupler carrier iron 3 is swingingly

mounted or suspended from the buffer block 2 by means of the arms 4 the lower ends of which are connected to the carrier iron by means of the bolt or like device 5. The 60 upper ends of the arms 4 are provided with a journal 6 which is journaled in a bearing 7 in the buffer block 2. The coupler 8 is of a standard type the draw bar of which is provided with lugs 9 on opposite sides 65 thereof which lugs may be attached to the draw bar by casting or any other practical manner.

The swinging carrier iron is provided with spaced lugs or ears between which is 70 journaled a stop or centering device 11 the upper end of the centering device or stop 11 being, preferably, at right angles to the body of the stop whereby an L shaped stop is formed said stop being free to swing on 75 the journal 12 secured to the ears 10. The stops 11 are of a width substantially equal to the width of the space between the opening in the buffer plate and the side walls of the draw bar when the draw bar is in line 80 with the center of the car as shown in Figure 2.

When the draw bar is in centered position as shown in Figure 2 one of the stops 11 is moved to position between the side walls 85 of the opening in the buffer block thereby substantially filling the said space and holding the coupler in centered position so that it will not fail to couple with a coupler of an on coming car. It will, of course, be 90 understood that it is only necessary to use the stop on the side of the coupler which is next to the inside of the curve or the lower rail, which by the way is the side on which the operator would stand. As soon as the 95 adjacent couplers are coupled the impact of coupling throws the two stops 11 to the inoperative position in which one of the stops is shown at the right hand side of Figure 2 whereby the coupler is free to 100 move sidewise with the swinging carrier iron 3 under service conditions. In the event that the stops 11 should for some reason become stuck and not fall by gravity under the impact of coupling the first pull 105 on the draw bar brings the lugs 9 in contact with the stops 11 and forces said stops out of the position shown in Figure 3 whereby they drop by gravity into inoperative position.

While for the purpose of illustrating my invention I have shown a particular form

of lug 9 and stop 11 it will of course be understood that changes in the construction of these elements may be made within the scope of the pending claims without departing from the spirit of my invention.

5. What I claim is:—

1. In a car, the combination of a coupler, of means to temporarily hold the coupler in proper coupling position while cars are being coupled, said means being released by impact or pull on the coupler.

10. 2. In a device of the character described, the combination with a car coupler laterally movable at its outer end with respect to the car, of means to temporarily hold the coupler in coupling position to receive a coupler of an on-coming car, said means being released by impact of the couplers or pull of the coupler whereby, when coupled to an 15 adjacent coupler, the coupler is free to move 20 sidewise under service conditions.

25. 3. In a device of the character described, the combination of a car coupler laterally movable at its outer end with respect to the car, a carrier iron upon which the outer end portion of the coupler is mounted, means to hold the coupler in line with the coupler of an adjacent car in the act of coupling, a means operated by the lengthwise movement 30 of the coupler to release said holding means, whereby the outer end of the coupler is free to move sidewise under service conditions when coupled to another coupler.

35. 4. In a device of the character described, the combination with a car coupler laterally movable at its outer end with respect to the

car, of a carrier iron upon which the outer end of the coupler is mounted, means mounted on the carrier iron to temporarily restrain the sidewise movement of the coupler, said 40 means being released by impact or pull on the coupler.

5. In a device of the character described, the combination with a coupler laterally movable at its outer end with respect to a 41 car, of a swinging carrier iron on which the outer end of the coupler is mounted, means carried by the carrier iron to temporarily restrain the sidewise movement of the coupler, and means operated by the coupler to 5 remove the restraining means out of the path of the sidewise movement of the coupler.

6. In a device of the character described, the combination with a car coupler laterally movable at its outer end with respect to the 5 car, of a carrier iron upon which the outer end of the coupler is mounted, means to temporarily restrain the sidewise movement of the coupler, and means carried by the coupler to move the restraining means to inoperative position.

7. In a device of the character described, the combination of a car coupler laterally movable at its outer end with respect to the car, of a stop on the carrier iron adapted to 6 temporarily restrain the sidewise movement of the coupler, and means carried by the coupler to move said stop to inoperative position.

In testimony whereof I affix my signature. 7

WALTER P. MURPHY.
